his atty.

UNITED STATES PATENT OFFICE.

JAMES BLUMER, OF NEW YORK, N. Y.

BOX-LID HOLDER.

No. 892,124.

Specification of Letters Patent.

Patented June 30, 1908.

Application filed April 25, 1907. Serial No. 370,143.

To all whom it may concern:

Be it known that I, JAMES BLUMER, a citizen of the United States, residing in the borough of Brooklyn, county of Kings, city 5 and State of New York, have invented an Improvement in Box-Lid Holders, of which the following is a specification.

My invention relates to a box lid holder and more particularly to that class of such 10 devices which are adapted to hold the hinged or other lid or cover of a box in a desired open position for the purpose of displaying the goods or articles contained in the box.

In carrying out my invention, my improved 15 box lid holder preferably comprises a stock member having a body portion and means associated therewith, whereby this stock member may be placed on and secured to the edge of the side of the box at one corner thereof, a lever arm pivotally connected to the said stock member, means at one end of the lever arm adapted to engage and support the cover or lid of the box, and means adapted to engage the opposite end of this 20 lever arm to secure the same in position and to determine the position in which the box lid is to be supported,—as will be hereinafter more particularly described.

In the drawing, Figure 1 is a side elevation 30 of my improved box lid holder showing the same applied to a box. Fig. 2 is an end elevation of the same. Fig. 3 is a plan of the same, and Fig. 4 is a sectional elevation on line x, x , Fig. 1, shown on a somewhat larger 35 scale.

Referring particularly to the drawing, the stock member of my improved box lid holder comprises a body portion a which may be made of sheet metal or any other suitable 40 material and preferably in the shape of a quadrant as illustrated. Attached to or integral with the body portion a is an arm member b which is parallel to and spaced apart from the said body portion, so that 45 these parts taken together are adapted to fit over and span the upper edge of one of the end members of the box, indicated by g .

The arm member b is provided with a lug c which may be integral therewith or otherwise 50 wise and turned at right angles thereto, so as to contact with and bear against the rear member of the box g . Moreover the arm b may be slotted as indicated at 10, making provision for the tongue d which is provided 55 with a projection 11 adapted to be forced into the inner surface of the end member of

the box to aid in securing the stock member thereon. The other side of the body member a or that which is adapted to assume a vertical position when placed upon the box is 60 provided with an arm e turned at right angles thereto and as is clearly shown in Fig. 2, adapted to contact with and bear against the outer surface of the rear member of the box; this member together with the lug c 65 bearing respectively as aforesaid against the outer and inner surfaces of the rear member of the box, provide against a shifting of the box lid holding device longitudinally on the end member of the box, while the body portion a and the arm b , together with the projection 11 provided in the tongue d , make provision for preventing the box lid holder from shifting upwardly on the end of the 70 box.

I also employ a lever arm h which is pivotally connected at 13 to the body portion a of the stock member and preferably this pivotal point is so placed as to be in line with the pivotal point of the hinge or hinges which 80 connect the box lid or cover 14 to the box. One end of the lever arm h is provided with outturned spring clamp jaws i adapted to fit over and engage a portion of the box lid or cover 14 and the opposite end of the lever 85 arm h is adapted to fit into the spaces 12 between the stops f provided on the curved edge of the body portion a respectively in equally spaced apart positions.

I claim as my invention:

1. In a box lid holder, two pivotally connected gripping members, the one comprising a lever-arm and means at one end thereof for gripping the edge of the box lid and the other comprising a stop having a body member, an arm turned at right angles to the body member and adapted to bear against the outer surface of the rear member of a box, an arm over-turned from and parallel with the said body member and provided with a lug adapted to bear against the inner surface of the rear member of the box, a tongue cut from the last aforesaid arm and adapted at its extremity to be forced into the end member of the box and means on the said body member for engaging the other end of the said lever-arm to determine the position in which the box lid is to be supported and to maintain the same therein.

2. In a box lid holder, two pivotally connected gripping members, the one comprising a lever-arm and means at one end thereof

for gripping the edge of the box lid and the other comprising a stop having a quadrant-shaped body member, an arm turned at right angles to the body member and adapted to bear against the outer surface of the rear member of a box, an arm over-turned from and parallel with the said body member and provided with a lug adapted to bear against the inner surface of the rear member of the box, a tongue cut from the last aforesaid arm and adapted at its extremity to be forced into the end member of the box and a series of spaced apart stops on the curved edge of the said quadrant-shaped body member with intermediate recesses adapted to receive the other end of the said lever-arm to determine the position in which the box lid is to be supported and to maintain the same therein.

3. A box lid holder comprising two pivotally connected gripping members, the one a quadrant-shaped body having means adapting it for connection with the body of the box at one side and the other a lever arm having means adapting it for connection with an edge of the hinged lid, the arc edge of the quadrant-shaped body having spaced apart turned up projections and the intervening recesses receiving the free end of the lever arm to adjust the raised position of the lid.

Signed by me this 18th day of December, 1906.

JAMES BLUMER
